UNITED STATES PATENT OFFICE

ROBERT F. DARBY, OF CHICAGO, ILLINOIS, ASSIGNOR TO AMERICAN STEEL FOUNDRIES, OF CHICAGO, ILLINOIS, A CORPORATION OF NEW JERSEY

GRATE

Application filed February 11, 1929. Serial No. 338,980.

This invention pertains to grates, and more particularly to the dumping or rocking type of multiple section grates used in locomotive fireboxes or the like.

5 There are special requirements for grates to be used in locomotive service which requirements are peculiar to that service alone and which must be constantly borne in mind to produce a successful device, especially as there 10 is an increasing tendency for long runs. One of these requirements is that the grates must be of sufficient width to allow rapid cleaning of the fire. In other words, when the grates are in dumping position, there must be an 15 open space between them large enough to freely pass all clinkers which have been formed. It is not uncommon to replace locomotive grate bars from time to time, the most common causes for replacement being—one: 20 burning of the top surface of the grates, and two: thermal cracks appearing in the top surface of the grates.

Burning or cracking of course necessitates the removal of the entire grate bar so burned 25 or cracked and is due to the fire coming into direct contact with the metal of the bar. The temperature of the fire being far above the fusing temperature of the metal usually used for these grate bars, large holes are produced 30 in the bars which in turn produce holes in the fire, which are very detrimental to proper combustion.

Thermal cracks are caused by unequal heating 35 of the grate bar structure. The usual design of structure has a top surface to support the fuel and admit air to the fuel bed, the structure being strengthened on the under side by deep ribs cast integral with the top, and the top surface is often in direct contact 40 with the fire while the strengthening ribs are kept comparatively cool by the rush of air through the grate bar to the fire. This produces a very unequal and bad condition of expansion and contraction in the casting, resulting 45 in thermal cracks in the top surface of the assembly. Once the cracks are started, it is only a question of time as to when they will extend all the way thru the casting, and for this reason grates must be inspected very 50 closely at terminals in order that the grate

bar may last as long as possible and yet be removed before it breaks, as a breakage on the road would cause "engine failure."

It is therefore desirable to design a grate 55 bar with a separate top which is in contact with and supports the fuel bed, said top being supported on a strength carrying member, and this strength carrying member would practically be a permanent part of the locomotive, while the top could be cheaply and quickly 60 removed for replacement.

It is therefore an object of the present invention to provide a grate assembly which is inexpensive to build and maintain, and one which fulfills all of the above enumerated 65 requirements for economical maintenance and successful operation.

Another object is to provide a grate bar assembly which effectively resists distortion, is readily removable and permits rapid cleaning of the fire and changes of the grate bars. 70

Still another object is to provide a grate assembly which affords substantially no resistance to expansion and contraction, yet at the same time is fixedly supported and effectively resists warping and twisting. 75

Yet another object is to provide a grate assembly wherein the securing members between parts are reduced to a minimum and wherein the clearances are predetermined and arranged to permit ease of operation, assemblage and replacement. 80

A further object is to provide a grate assembly wherein the table grates are interchangeable and the clearances are predetermined by said table grates. 85

A still further object is to provide a grate frame or load carrying member which is of ample strength, is air cooled to the greatest possible degree, is designed to hold the top plates firmly in place and yet allows for full expansion and contraction, and finally one which is inexpensive to produce. 90

A yet further object is to provide a table grate or plate for cooperation with a frame 95 fulfilling the above requirements, said plate being adapted for the uniform admission of air through said plate for proper combustion, the plate being of uniform thickness yet as thin as consistent with strength and 100

rigidity, to the end that the shrinkage stresses are reduced to a minimum. Further, the plate is designed for free expansion and contraction without affecting the frame, 5 is of such character that the production variations do not materially affect the proper function or firmness of the fastenings of the top to the frame, and the plate is of such character as is easily and inexpensively removed and replaced.

With these and various other objects in view, the invention may consist of certain novel features of construction and operation, 15 as will be more fully described and particularly pointed out in the specification, drawings and claims appended hereto.

In the drawings, which illustrate an embodiment of the device and wherein like reference characters are used to designate like parts:

Figure 1 is a top plan view, showing the supporting relation of the grate frame to one of the grate plate members, and indicating relation between a pair of grate plate members;

Figure 2 is a side elevation of the grate assembly shown in Figure 1;

Figure 3 is an end elevation of the grate assembly indicated in Figure 1;

Figure 4 is a sectional end elevation of the grate assembly shown in Figure 1, the same being taken substantially in the plane as indicated by the line 4—4 of Figure 1;

Figure 5 is a sectional side elevation of a modified form of assembly, the same showing various positions of assembly of the table grates or plates with the support;

Figure 6 is a fragmentary top plan view of the modified form of grate plate support shown in Figure 5;

Figure 7 is a fragmentary sectional side elevation of a portion of a grate assembly, the same being taken substantially in the plane as indicated by the line 7—7 of Figure 6;

Figure 8 is an end elevation of a modified form of end securing means between the parts of the grate assembly;

Figure 9 is a fragmentary top plan view of a portion of the supporting member of the grate assembly illustrated in Figure 8;

Figure 10 is a top plan view of another modified form of the grate assembly;

Figure 11 is a side elevation, partly in section, of the assembly illustrated in Figure 10; and

Figure 12 is a sectional end elevation of the grate assembly illustrated in Figure 10, 60 the same being taken substantially in the plane as indicated by the line 12—12 of Figure 10.

Referring first of all more particularly to the modification illustrated in Figures 1 to 4 65 inclusive, the supporting frame 20 of the

grate assembly comprises a single longitudinal rib 22 of substantial truss shape, said rib being shown as provided at the ends thereof with horseshoe sockets 24. As will be seen, the longitudinal rib 22 is given the greatest 70 depth adjacent the center and therefore the construction approaches a beam of uniform strength; in other words, having uniform internal fiber stresses. The sockets or trunnions are each shown as provided with up-standing bosses 26 which extend to a height above the rib 22 corresponding substantially to the height of the grate assembly with the grate plates in place. The bosses are provided with sloping side portions 28 to provide proper draft spaces after the plates are assembled, and outwardly extending securing lugs 30 are provided adjacent the ends of said trunnion and preferably on the same level as the top of the rib 22. It will be seen 80 that the surfaces 28 are joined to the frame at a knuckle or shoulder 31, said shoulder providing means for insuring unobstructed draft and also being formed for the purpose of facilitating casting of said frame in that such formation makes for a clean casting preventing formation of burrs or rounded portions on the frame.

As is shown, the plate support is provided 95 for cooperative relation with a pair of grate plates only, though it is to be understood that it may be adapted to use any number of plates. In this instance then, outwardly extending securing lugs 32 are provided adjacent the center of the support, each of said lugs being provided with apertures 34 for the reception of lugs provided on the grate plates.

As shown in Figure 2, the supporting rib 105 may be provided with a pair of spaced apertures 36 for a shaker arm 38, which shaker arm is formed with spaced embracing jaws 40 of substantial Z-section, each of said jaws being provided with an aperture adapted to register with one of the apertures 36 for the reception of securing means, such as the rivets 42, so that it will be seen that with this construction, the shaker arm 38 is reversible.

In this construction, the center of gravity 115 of the entire grate assembly is materially lowered by providing grate plates 50 with a flat top having openings 52 disposing portions of the grate plates in embracing relation with respect to the upstanding boss 26. These openings 52 are so proportioned as to give ample clearance, as indicated at 54 in Figure 4, whereby a generous draft space is provided which permits ashes to readily pass therethrough. The plate is preferably provided with faced lugs or bosses 56 adapted to be disposed in close proximity to the boss 26 to cut down excessive transverse working or relative movement between the plate and the frame. The plate shown is provided with marginal 120 125 130

flanges 58, the side flanges or ribs being of substantial truss shape and being provided at the ends thereof with depending facing hooks 60 adapted to engage under the lugs 30 when the plates are in operative position with respect to the frame, it being seen that there is no clearance between the top or ledge of the hooks 60 and the bottom of the lugs 30, whereas a generous clearance is provided above the lugs 30 and between the plate. The flange provided with the hooks 60 is of course interrupted by said hooks and by the aperture 52 embracing the boss 26, but the marginal flange 62 is preferably provided embracing the boss 15 and forming a seat on the extended lug portion 64 on the trunnion 24. The other end marginal flange 66 forms a seat on the frame and on the lugs 32, and said flange is provided with depending securing lugs 68 apertured 20 for the reception of the locking key 70 passing through adjacent lugs 68 of a pair of grate plates. Each of the grate plates is also provided with a boss 72 adapted to abut the adjacent grate plate for maintaining said grate plates in proper operative position. Each grate plate is provided with spaced apertures 74 providing draft openings, and the longitudinal marginal flanges are provided with reinforcing ribs 76 spaced thereon and integral with the top of the grate plate. Local reinforcing ribs 78 may also be provided adjacent the longitudinal center line of the grate plate, preferably disposed in staggered relation with respect to the reinforcing ribs 76 and adapted to contact the frame for supporting the grate plate.

In the modification illustrated in Figures 5 to 7 inclusive, the supporting frame 100 is provided with the oppositely extending central lug 102 corresponding and functioning in a manner similar to lugs 32, said lugs being apertured at 104. The frame may also be of truss shape and is provided with the trunnions 106 at the ends thereof and also outwardly extending supporting lugs 108. The frame between the trunnion 106 and the rib 100 is widened as at 110 and is provided with a slot 112 having an overhang or hook engaging portion 114. The grate plates 116 are provided with marginal flanges 118, central reinforcing supports 120 and end lugs 122, corresponding to lugs 68 and being apertured for the reception of a securing key. The plates are also provided with spacing bosses 124 similar to and functioning in a manner as already described with respect to the bosses 72. In this case, the grate plates are provided with a single longitudinal hook 126 adapted to be inserted in the slot 112 and having a portion engaging the overhang 114.

This modification may also be adapted for use with transversely extending hooks 150, in which case the longitudinal rib 152 is provided with end trunnions 154 having out-

wardly extending lugs 156 and supporting portions 158, sloping portions 160 and 162 being for the purpose of providing draft clearances. The hooks 150 then provided on the grate plates 164, engage under the lugs 156 in a manner already described for the hooks 60 and their engagement with their lugs 30, it being understood that depending lugs similar to the lugs 68 are provided on the plate for securing the opposite end of said plate to the frame.

Referring now more particularly to the modification illustrated in Figures 10 to 12 inclusive, the supporting frame 200 includes a pair of spaced parallel longitudinal ribs 202 joined at one end thereof by a trunnion socket 204 and at the other end by a horseshoe socket 206. As before, these ribs 202 are shown as of substantially truss shape. The sockets are provided with a longitudinal slot 208 having an overhang or hook engaging portion 210, and the ribs 202 are provided with horizontally and outwardly extending lugs 212 apertured at 214 and similar to the lugs 32 already described, the upper surface of the lugs being continuous with the upper surface of the ribs 202. Inwardly projecting bosses or lugs 216 may be provided adjacent the lugs 212 for supporting relation with the plates, and additional outwardly projecting supporting lugs 218 may be provided adjacent the ends of the frame.

As shown, this assembly may consist of a supporting frame and a plurality (shown 2) of supported perforated grate plates 220, either of flat or arcuate form. These grate plates are identical in design and construction and are interchangeable as in the case of the other modifications, and have a convex or arched upper surface and are provided on the opposite or under surface with a longitudinal reinforcing rib 222, a transverse reinforcing rib 224 removed from the plate margin, longitudinal marginal ribs 226, and a transverse marginal rib 228. The grates are provided with centrally disposed outwardly and downwardly extending hook lugs 230 similar to the hooks 126, said hook lugs 230 being preferably disposed adjacent the rib and integral therewith. The opposite end of the grate plate is provided with spaced apertured lugs 232 extending downwardly from the marginal rib 228, which lugs are of a spacing to permit their insertion into the apertures 214.

When the grate plate and grate frame are in assembled position, the hook lug 230 extends under and engages the overhanging shoulder 210 of the slot 208, being positioned by the slot while the lugs 232 are being positioned in the horizontal lugs 212. Lugs 232 are provided with key slots 234 adapted to receiving locking keys 236 which when driven home lock the supporting frame and plates in a unit assembly, it being seen that one key

serves to lock one side of a pair of plates, as is the case in the other modifications. The plates are each provided with a spacing boss 238 preferably located at one corner of the plates integral with the transverse rib 228 and extending longitudinally of the plate. When the ribs are in operative position, the bosses abut a portion of the rib 228 on the adjacent plate and act as limiting clearance means between the plate when in their assembled position, providing a constant air space and facilitating assemblage of the parts. The openings 212, as in the case of the openings 104 and 34, are preferably of rectangular form and are of a width equaling substantially twice the thickness of the depending lugs on the plates plus the depth of the bosses 72, 124 and 238 respectively, and twice the amount of plate clearance.

In all of the modifications shown, it is found convenient to first slip the securing member or hook of the grate plate into engagement with its respective holding member, as for instance, slipping the hooks 60 beneath the lugs 30 (Figures 1 to 4 inclusive), slipping the hooks 126 beneath the overhang 114 (Figures 1 to 6 inclusive), and in slipping hooks 230 beneath the overhang 210 (Figures 10 to 12 inclusive), and then lowering the opposite end of the plate into place where its projecting lugs will register with the locking members or lugs 32, 102, 212 respectively on the frame. The other plate is lowered into place in the same manner, the various positions thereof being shown in Figure 5, and after said plate is in place, locking is effected by means of the keys disposed through registering apertures of the depending lugs of adjacent grate plates, it being seen that one key is used to lock each of the pairs of adjacent lugs on said plates, and with such construction, it does not matter whether the hooks and their overhanging portion of the frame are of correct dimensions or not for the plates can readily be forced into position by merely applying weight to the inner ends of said plates whereupon it will be seen that because of the tight fit and of the contact between the various supporting ribs on the plate contacting with the supporting rib or ribs of the frame, warping is effectively prevented, yet on account of the assembly and the disposition of the ribs, there is no obstruction placed in way of full and efficient draft and relative working of the parts is prevented.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In an assembly of the character de-

scribed, in combination with a grate bar and a supporting frame, locking and positioning means including a shoulder on said supporting frame, a hooked lug formed on the underside of said grate bar and engageable with said shoulder, two horizontally projecting apertured lugs provided on said supporting frame, downwardly projecting apertured lugs on the under side of said grate bar engaging with said supporting frame lugs, and fastening means positioned in said apertures of said projecting grate member lugs.

2. In a grate assembly, the combination of a supporting frame comprising spaced parallel beams, integral trunnion sockets located at opposite ends of said parallel beams and uniting the same, reinforced grate members resting upon and carried by said supporting frame, downwardly extending apertured lugs on the inner end of each of said grate members, horizontally projecting apertured lugs provided on said supporting frame and embracing said downwardly extending lugs of said grate member, and a plurality of cotter keys positioned in said downwardly projecting lugs and bearing against the under surface of said horizontal lugs for securing said grate member and said supporting frame in a locked, assembled and operative position.

3. In a grate assembly, the combination of a support having trunnion sockets formed thereon, aligned securing means spaced from said sockets, a recessed portion adjacent said sockets, supporting means on said support disposed adjacent said sockets and said securing means, grate members carried by said support and having portions engaging said supporting means, said grate members having means lockingly engaging said recessed portion, and means cooperating with said aligned securing means for maintaining said grate members in operative position, said grate members having means for maintaining the same in spaced relation.

4. In a grate assembly, the combination of a support having trunnion sockets formed thereon, aligned securing means spaced from said sockets, a recessed portion adjacent said sockets, supporting means on said support disposed adjacent said sockets and said securing means, grate members carried by said support and having portions engaging said supporting means, said grate members having means lockingly engaging said recessed portion, and means cooperating with said aligned securing means for maintaining said grate members in operative position, said grate members having bosses engaging the adjacent grate members for maintaining said members in spaced relation.

Signed at Chicago, Illinois, this 26th day of January, 1929.

ROBERT F. DARBY.
